EDWIN W. KELLY, OF PHILADELPHIA, PENNSYLVANIA.

RADIATION-SHIELD.

1,156,906.

Specification of Letters Patent.

Patented Oct. 19, 1915.

Application filed November 18, 1912. Serial No. 732,055.

To all whom it may concern:

Be it known that I, EDWIN W. KELLY, a citizen of the United States, residing in the city of Philadelphia, county of Philadelphia, 5 and State of Pennsylvania, have invented certain new and useful Improvements in Radiation-Shields, of which the following is a specification.

It is the object of my invention to provide means for shielding an operator from harmful radiations, such as X-rays. To this end I provide a box or inclosure for the source of radiations, such as an X-ray tube, which is provided with lead or other ray 15 absorptive material graded or varied as to its thickness, and therefore as to absorptive power, according to the locality of the absorptive material with respect to the source of radiations, this being, in the case of an 20 X-ray tube, the focus spot on the target.

By my invention I am enabled to protect an operator from the primary radiations, as well as secondary, tertiary and other radiations with relatively small amount of ray 25 absorptive material, with the result that the apparatus is both cheapened and lightened in weight.

For an illustration of one of the forms my invention may take reference is to be had to 30 the accompanying drawings, in which:

Figure 1 is a vertical sectional view through a shield box and its ray absorptive material, some parts shown in elevation. Fig. 2 is a fragmentary front elevational 35 view of the apparatus shown in Fig. 1. Fig. 3 is a horizontal sectional view, taken on the lines A—A of Fig. 1.

The X-ray tube X is supported by any suitable means within the box B of wood or 40 any other suitable material. The X-ray tube comprises the usual target or anode *a* and cathode *k*, and vacuum regulator *r*.

As well understood in connection with X-rays, these rays exist substantially entirely 45 in a hemisphere bounded by a plane embracing and coincident with the plane of the face of target *a*, such plane being represented by a dotted line *p*, Fig. 1. The rays in this hemisphere are substantially all primary or direct rays and are the effective rays 50 for X-ray operations or investigations and are at the same time the most harmful to the operator.

The front of the box B has an aperture *b* 55 and registering with this aperture *b* is the aperture *c* in the plate or casting C of lead

or any other suitable ray absorptive material.

The thickness of the plate or casting C is a maximum where it is nearest the focus 60 spot *f* on the anode or target *a* and diminishes in thickness in all directions, upwardly, downwardly, and laterally as indicated in Figs. 1, 2 and 3. The thickness at all points is however sufficient to absorb practically all 65 the primary rays impinging upon the inside of the plate or casting C, and all secondary or tertiary rays that may impinge upon it. The thickness of the plate C at any point is a function of the distance of that point from 70 focus spot *f*.

The plate or casting C is secured to the front of the box or support B by any suitable means such as screws 1, 1 Fig. 2. At its top and at the center may be provided a lug 75 2 as suitable means for grasping the plate C or attaching thereto any means for lifting it and handling it. Extending downwardly from the lug 2 may be provided a rib 3 terminating in the lug 4, a similar lug 5 being provided below the aperture *c*. On these lugs are pivoted the bars 6 and 7 pivoted at their outer ends to the bars 8 and 9, forming a parallelogram motion for moving vertically the diaphragm plates 18 and 19, preferably of lead, attached to these bars 8 and 9. As to the operation of the shutter or diaphragm it will be noted that each of the pivoted bars carries one diaphragm element and that as the parallelograms are flattened 90 these members approach each other. And similarly the laterally disposed lugs 12 and 13 are provided upon the plate C, and upon these lugs are pivoted bars 14 and 15 pivoted at their outer ends to the bars 16 and 17, 95 constituting a parallelogram motion for moving the diaphragm members 10 and 11 attached to the bars 16 and 17 respectively.

The bar 17 has an extension 20 and the bar 8 has an extension 21 by which these parallelogram motions may be actuated to move the diaphragm members to adjust the extent of aperture between for purposes of more or less restricting the field of the X-rays passing from the target *a* through the aperture *c* to the object under investigation.

On each side of the box B is provided a plate or casting D, of lead or other suitable ray absorptive material. The upper edges of these plates D slant downwardly and backwardly from the front of the box as indicated by the dotted line in Fig. 1, such edge

being substantially parallel with the plane of the target α but some distance back of or above the plane of the target α shown in Fig. 1.

5 The plate C on the front of the box extends upwardly beyond the plane of the target α , as indicated in Fig. 1. Above the plate C is a relatively thin plate E, of lead or other suitable absorptive material applied to the box B and extending over its top as shown in Fig. 1, and on the sides above plates D. In this region well back of the plane of the target α and in what may be called the inactive hemisphere, there 10 practically are no direct radiations, but only secondary or tertiary radiations, which are completely absorbed by the thin sheet metal E. On the bottom of the box B, as shown in Fig. 1, is provided a sheet of metal F, 15 of lead or other suitable ray absorptive material which is preferably thicker than the sheet metal E because the plate F is within the active hemisphere, but of such substantially uniform distance from the focus spot f that little or no economy would be effected 20 by changing its thickness with the variations in distance of its parts from the spot f .

The plate C has flanges 22 embracing the 30 edges of the plate D clearly shown in section in Fig. 3, and as these plates D are of varying thickness, as explained, these flanges 22 extend from varying widths of the plate C as indicated in Fig. 2. The box 35 B may be provided with a removable or hinged cover G carrying the blocks of wood or other material 23 through which extend the rubber or other insulating rods 24, 25 and 26 inclosing the conductors 27, 28 and 40 29 respectively, which connect with the positive terminal 30, the vacuum regulator terminal 31 and the negative terminal 32 of the X-ray tube X.

The cover G is provided with a sheet H, 45 of lead or any other ray absorptive material extending over its top, back and sides within the inactive hemisphere back of the plane of the target α . On the back, bottom and sides of the cover G, within the active 50 hemisphere, is a sheet J of lead or other ray absorptive material, of greater thickness than the sheet H because disposed within the active hemisphere. In the sheets H and J are provided apertures 33 and 34 around 55 the rods 24, 25 and 26, these apertures being large enough to prevent the short circuiting of the high tension current from the conductors 27 and 29 to each other through the metallic sheeting. Due to these apertures however there is a possibility of escaping from 60 within the box of some of the rays. Through the aperture 34 there would escape some direct or primary rays were it not for the fact that there is disposed in the path of 65 such rays absorptive material such as the

sheets of lead glass 35 and 36 carried by the block 23 and of such size and so positioned as to prevent rays escaping through the aperture 34 through the wood 23 and the cover G. The aperture 33 is in the inactive hemisphere where the radiations are far weaker and in this case a single sheet of lead glass 37 is supported upon the upper block 23 of such dimensions and in such position as to prevent rays escaping through the aperture 70 33. For the sheets of lead glass 35, 36 and 37 other ray absorptive material may be employed as, for example, sheets of lead.

It will be noted that the absorptive material of varying thickness, varies in thickness 80 in a direction of a rectilinear ray from the focus spot f with distance from such focus spot, and simultaneously varies in thickness in a direction normal to the surface of the support, as the flat outer surface of the 85 box B.

From the foregoing description it is apparent that I have provided means for shielding against primary, secondary, tertiary and lesser radiations by the employment of a relatively small amount of ray absorptive material with resulting cheapening and lightening of weight of the ray absorptive material and of the apparatus as a whole; the lightening of weight being of 90 further importance because of frequent need for moving the X-ray tube and its shield as a unit.

What I claim is.

1. The combination with an X-ray tube, 100 of a shield inclosing the same and comprising a mass of ray absorptive material varying in thickness between its inner and outer faces with distance from the focus spot of said tube and varying in thickness in a 105 radial direction from said focus spot with distance from said focus spot.

2. The combination with an X-ray tube, 110 of a shield support having a surface varying in distance from the focus spot of said tube, a shield comprising ray absorptive material disposed upon said surface, said ray absorptive material having different thicknesses measured normally to said surface and different thicknesses measured 115 radially from the focus spot of said tube.

3. The combination with an X-ray tube, 120 of a shield support having a surface varying in distance from the focus spot of said tube, a shield comprising ray absorptive material disposed upon said surface, said ray absorptive material having different thicknesses measured normally to said surface and different thicknesses measured radially from the focus spot of said tube, 125 said thicknesses diminishing with increasing distances from the focus spot of said tube.

4. The combination with an X-ray tube, 130 of a shield support therefor comprising a

member having a substantially flat surface, a shield of ray absorptive material disposed upon said surface, said ray absorptive material diminishing in thickness normally to 5 said surface and radially from the focus spot of said tube with increasing distances from the focus spot of said tube.

5. The combination with an X-ray tube, of a shield therefor comprising a support, 10 ray absorptive material having an aperture in front of the focus spot of said tube, said ray absorptive material diminishing in thickness in a direction away from said aperture, a sheet of ray absorptive material 15 on said support in the active hemisphere in front of the focus spot, and a sheet of ray absorptive material of different thickness on said support back of said focus spot.

6. The combination with an X-ray tube, 20 of a box inclosing the same, a sheet of conductive ray absorptive material disposed upon a wall of said box, said sheet having apertures, conductors extending to the terminals of said tube through said apertures 25 and spaced in said apertures from said material, and ray absorptive material interposed between said apertures and said tube.

7. The combination with an X-ray tube, 30 of a conductor communicating with a terminal thereof, ray absorptive material having an aperture through which said conductor passes, and ray absorptive material intervening between said aperture and said X-ray tube.

35 8. The combination with an X-ray tube, of a substantially flat shield member of ray absorptive material associated therewith, said member having an aperture through which direct rays may be passed, said member diminishing in thickness in a direction away from said aperture, and a diaphragm 40 of ray absorptive material supported on said member.

9. The combination with an X-ray tube, 45 of a box inclosing the same, a coating of ray absorptive material on the walls of said box, the thickness of said ray absorptive material diminishing with the distance of said material from the focus spot of said tube.

10. The combination with an X-ray tube, 50 of a shield therefor comprising ray-absorptive material inclosing said tube and disposed at varying distances from the focus spot thereof, said ray-absorptive material within the active hemisphere diminishing 55 in thickness from the region nearest said focus spot to the plane bounding said hemisphere.

11. The combination with an X-ray tube, 60 of a shield therefor comprising ray-absorptive material inclosing said tube and disposed at varying distances from the focus spot thereof, said ray-absorptive material within the active hemisphere diminishing in thickness from the region nearest said focus 65 spot to the plane bounding said hemisphere, and the ray-absorptive material back of said plane being relatively thin and of substantially uniform thickness.

12. The combination with an X-ray tube, 70 of a box and its cover, ray-absorptive material inclosing said tube carried by the walls of said box, said walls being substantially flat, and said ray-absorptive material diminishing in thickness from the region 75 nearest the focus spot of said tube to the plane bounding the active hemisphere.

13. The combination with an X-ray tube, 80 of a box having front and sides inclosing said tube, the walls of said box being substantially flat, ray absorptive material disposed upon the front and sides of said box, the ray absorptive material in front of said box diminishing in thickness with distance from the focus spot of said tube, masses of 85 ray absorptive material on the sides of said box and having edges slanting substantially parallel with the face of the target of said tube, said last named masses diminishing in thickness with distance from the focus spot 90 of said tube.

In testimony whereof I have hereunto affixed my signature in the presence of the two subscribing witnesses.

EDWIN W. KELLY.
